UNITED STATES PATENT OFFICE

THOMAS M. BUTLER, OF DETROIT, MICHIGAN, ASSIGNOR TO BURROUGHS ADDING MACHINE COMPANY, OF DETROIT, MICHIGAN, A CORPORATION OF MICHIGAN

CASH DRAWER AND SIGNAL THEREFOR

Application filed January 18, 1928. Serial No. 247,524.

This invention relates to a cash drawer and signal therefor.

The general object of the invention is to provide an improved cash drawer for use with calculating machines.

Another object is to provide an improved signal mechanism for a cash drawer.

Other objects and advantages of the invention will appear hereinafter.

10 An embodiment of the invention is shown in the accompanying drawings in which—

Figure 1 is a longitudinal sectional view through the cash drawer showing the means for operating it as well as the signal mechanism.

15 Fig. 2 is a transverse section taken at right angles to Fig. 1 looking toward the rear of the drawer, some of the parts being broken away.

20 Fig. 3 is a perspective view of the signal mechanism when the parts are in normal position.

Fig. 4 is a perspective view similar to Fig. 3, showing the position of the signal mechanism when the cash drawer is partly open and before the signal mechanism has operated.

25 Fig. 5 is a perspective view similar to Fig. 3 showing the position of the parts after the signal mechanism has been operated and as the cash drawer is returning to its normal position.

30 Figs. 6, 7, 8 and 9 are diagrammatic views illustrating how the signal mechanism is operated.

Fig. 10 is a perspective view of the connection for the spring used for opening the drawer.

40 Fig. 11 is a separated perspective of a portion of the bottom of the drawer and the frame for receiving it showing how the parts fit together in sliding relation.

The cash drawer 10 is mounted within a housing 11 adapted to support a calculating machine the base of which is shown at 12 and the casing at 13. Positioned in the housing are front and rear U-shaped members 14 (Fig. 2) which are attached to a base 15 by screws 16 (Fig. 1) which also hold the feet 17 on the bottom of the base plate. Jour-

naled on studs 18 carried by the upwardly projecting arms of the U-shaped members 14 are rollers 19 on which run the flanges 20 of the cash drawer.

The cash drawer has a front 21, two transverse partitions 22 and 23, a rear end 24 and a top portion 25. It is also provided with two longitudinal partitions 26 and 27 illustrated in Fig. 2.

55 The U-shaped members 14 also support the 60 housing 11 which is attached thereto by screws 28. This housing surrounds the rear and the two sides of the framework together with the front end except for the opening 29 (Fig. 1) for the cash drawer 10. This housing has a lower flange 30 extending over the base 15 and an upper flange 31 fitting outside of the base 12 of the calculating machine.

65 The calculating machine is supported on 70 the cross members 32 and 33 which in turn are fixed to the sides of the housing 11. The casing 13 of the calculating machine extends over the flange 31 of the housing as illustrated in Fig. 1.

75 The cash drawer is urged outwardly by a 80 spring 40 connected at one end to a stud 41 on a stationary guide rail 42 supported by the posts 43 on the base of the U-shaped members 14. The other end of the spring is connected to a clip 44 illustrated in detail in Fig. 10. The forward portion of this clip has a downwardly extending lug 45 to receive the spring 40 and an upwardly extending lug 46 which has a bent-over end engaging the 85 under side of the guide rail 42. The clip is also provided with two lugs 47 extending downwardly from its rearward portion, said lugs bearing against the side edges of the rail 42. The upper and rear portion of the 90 clip has a bent-over projection 48 surrounding a leather cushioning block 49. This cushioning block bears against an angle-shaped member 50 attached to the rear of the cash drawer 10, the upper end of said member extending over the top of the drawer as illustrated in Fig. 1. The lower end of the member 50 has a T-shaped opening to receive the guide rail 42 as illustrated in Figs. 2 and 11. The guide rail 42 has a stop lug 52 on its 10

bottom side near the center which limits the forward movement of the clip 44 when the projection 46 on the spring clip 44 strikes it as the cash drawer is propelled outwardly.

- 5 The drawer is normally prevented from moving out by a latch 53 having a shoulder 54 (Fig. 3) which engages the rear end of a slot 55 in the top part of the member 50. The latch is fixed to a shaft 56 journaled in brackets 57 and it extends outward to the right side of the cash drawer structure as illustrated in Fig. 2, where it has fixed to it an arm 58 connected by a link 59 with a trip lever 60 pivoted at 61. By pulling the lever 60 forwardly the latch 53 is raised thereby releasing the cash drawer whereupon it is immediately propelled forward by the force of the spring 40 until the spring clip 44 is arrested by the stud 52. When the drawer 20 is pushed inwardly again it is automatically locked in position by the latch 53 which is urged downwardly to latching position by the spring 62 connected to the arm 60 as illustrated in Fig. 1.
- 25 The cash drawer signal includes a bell 70 supported at 71 on the rear of the housing 11. The bell is rung by means of a striker pivoted at 72 to a stud on the rear of the housing 11. This striker has an operating arm 73 and a striking arm 74 with a striking head 75 upon it. The striker is normally held so that the head 75 is slightly out of engagement with the bell 70 as shown in Fig. 2, by means of a spring 76 connected at one 30 end to the stud 77 on the arm 74 and at the other end to a stud 78 fixed to the rear of the housing 11.
- 35 The bell ringing member 73-74 is operated by means of a cam 80 pivoted at 81 to lugs 82 extending outwardly from the member 50 on the cash drawer. The cam 80 has an angular cam edge 83 for contacting the edge of the arm 73 and its outer end is bent upwardly to provide a cam surface 84 for 40 contacting the top of the arm 73, to thereby rock the cam clockwise (Fig. 5) so that the cam 80 will ride over arm 73 and drop into its Fig. 3 position when the drawer is fully moved inwardly. The bell ringing parts 45 operate as follows:

50 The normal position of the parts with the cash drawer closed is illustrated in Fig. 3 and diagrammatically in Fig. 6. As the cash drawer opens the member 80 moves with it 55 and the inclined surface 83 engages the edge of the arm 73 as illustrated in Figs. 4 and 7, to move said arm clockwise from the position of Fig. 3, toward the Fig. 4 position which rocks the striker 73-74 clockwise and 60 tensions the spring 76. As the end of the surface 83 of cam 80 clears the arm 73 (Fig. 8), the striker 73-74 is suddenly released whereupon the spring 76 draws it downwardly very suddenly and causes its hammer end 75 to strike the bell a sharp percussive blow

to ring it. Spring 76 immediately raises the hammer from the bell surface thereby leaving the bell free to vibrate.

As the cash drawer is pushed to closed position, the turned up end 84 of the cam 80 strikes the top of the arm 73 as illustrated in Figs. 5 and 9 and, owing to the fact that the member 80 is pivoted, said member turns upwardly and passes over the arm 73 without affecting the position of the striker 73-74. After the cam 80 has passed over the arm 73, it drops back by gravity to the normal position illustrated in Fig. 3. The parts are then ready for another bell ringing operation.

An important feature of the signal construction is that the signal device is made out of a minimum number of parts, there being only one striker and one actuating member therefor instead of a complicated series of devices for ringing the bell.

Means is also provided for preventing the drawer from being entirely removed except through the manipulation of a special latching means that is hidden from view.

Located inside the drawer at its rear end, as illustrated in Fig. 2, is a shaft 90, one end of which is slidably mounted in an opening 91 in the side 10 and the other end of which is positioned in an opening 92 in the partition plate 26, both of said openings 91 and 92 being just slightly larger than the diameter of the shaft so as to accommodate it without binding. The right hand end of the shaft as viewed in Fig. 2 has two reduced portions 93 and 94 joined by an enlarged portion 95 which, however, is of less diameter than the diameter of the main part of the shaft. These reduced portions form annular recesses that serve to hold the shaft in its different positions by engaging the edge of the opening 92 in the partition plate. The shaft is urged downward at its right hand end by a spring 96, one end of which is connected to the shaft and the other end to a stud 97 on the rear of the drawer. The shaft normally occupies the position illustrated in Fig. 2 where it will be observed that its left-hand end projects beyond the side of the drawer sufficiently to contact the roller 19 when the drawer is pulled out. The shaft thus prevents the drawer from being completely removed, but by reaching inside the drawer, lifting the right hand end of the shaft, and sliding the shaft to the right until the recess 93 engages over the edge of the opening 92,

110 the drawer may be released because, under such conditions, the left hand end of the shaft 90 no longer projects beyond the side of the drawer and hence does not strike the roller 19 to prevent removal. To anyone familiar with the drawer this provides an easy method for complete removal of it, but it likewise prevents those unfamiliar with the construction from removing it. In order to prevent the shaft 90 from becoming mis-

placed, through being moved too far in either direction, a lug 98 struck from the rear of the drawer is bent over the shaft to limit its upward movement. With the left hand end of the shaft in the opening 91, the lug is positioned so that the right hand end of the shaft may be raised high enough to allow the portion 95 of the right hand end of the shaft to be moved through the opening 92, but it does not permit the shaft to be raised high enough to permit the end 99, which is of the same diameter as the main body of the shaft, to be moved through the opening 92. Likewise, it does not permit the main body of the shaft to be moved to the right through the opening 92. Accordingly, the shaft is effectively prevented from being accidentally misplaced through mis-operation.

It is to be understood that the construction shown is for purposes of illustration and that variations may be made in it without departing from the spirit and scope of the invention as defined by the appended claims.

I claim:

25 1. In combination, a metal cash drawer having supporting rails, longitudinally U-shaped members carrying rollers on which said rails travel, a housing for the cash drawer supported by said U-shaped members, a 30 spring connected to the rear of the drawer and to a stationary fastening at the front of the housing, a latch for holding said drawer within the housing against the tension of the spring, means for releasing the latch, and a 35 stop for limiting the outward movement of the drawer.

2. In combination, a metal cash drawer having supporting rails, longitudinally U-shaped members carrying rollers on which 40 said rails travel, a housing supported by said U-shaped members, a bottom guide rail positioned beneath the center of the drawer, a guiding member carried by the rear of the drawer and co-operating with said guide 45 rail, a spring connected to a clip bearing against said guiding member and to a projection at the forward end of the guide rail, a latch for holding said drawer in the housing against the tension of the spring, and a 50 stop on the guide rail positioned to limit the outward movement of said clip.

3. In combination, a base plate, longitudinally U-shaped members connected to said base plate and supporting rollers, a metal 55 cash drawer having rails traveling on said rollers, a housing for enclosing said cash drawer supported by said U-shaped members, a guide rail beneath the center of the cash drawer, a guiding member on the rear 60 of said drawer co-operating with said guide rail, a spring connected to a clip bearing against said guide member and to a projection on the forward end of the guide rail, a latch for holding said drawer within said 65 housing against the tension of said spring,

and a stop on the guide rail for limiting the outward movement of said clip.

4. In combination, a metal cash drawer, a housing within which said drawer operates, a center guide rail beneath said drawer, a 70 guide member on the rear of the drawer co-operating with the guide rail, a spring clip bearing against said guide member, a spring connected to said clip and to a projection at the forward end of the guide rail to urge the 75 clip and drawer outwardly, and a stop on said guide rail to limit the outward movement of the clip.

In testimony whereof I have subscribed my name.

THOMAS M. BUTLER.
